DEVICE FOR PROTECTING METAL FROM CORROSION

Harry Mogck, Cape May, N. J.

Application June 5, 1945, Serial No. 597,701

4 Claims. (Cl. 204—197)

1

This invention relates to metal protective device and method and relates particularly to a device and method of the character described by which it is possible to protect, from the deleterious effects of electrolysis, metal conduits and metal walls of parts through which, and around which, water is introduced or circulated.

Heretofore it has been realized that raw sea water has a detrimental effect upon the cooling circulatory systems of engines used in water-craft of various kinds, and attempts have been made to prevent damage to metal walls of various parts of the engine with which water must come into contact.

For example, it is well known that the use of fresh water will decrease, by many times, the rate of destruction experienced because of electrolysis and corrosion when raw sea water is used. Therefore, in many instances, a boat may be provided with an adequate reservoir for fresh water which will be run through the cooling jackets of the engine; thence through a radiator of some type located at some distance to effect dissipation of heat. Such an arrangement is not only costly, but bulky, uneconomical, and lacking in the degree of positive effectiveness which comes about through using, from the ocean itself, in as great quantities as needed, an always available supply of cooling medium of relatively low temperature.

In order to obtain the advantages given by using sea water as a cooling medium, and yet to avoid deleterious effects of sea water upon the circulatory systems of engines, it has been quite common to run fresh water through the circulatory system of the engine and then to cool the fresh water by running it through a heat exchanger, which uses as its cooling medium raw sea water of low temperature.

While the engine parts in such systems are protected adequately, during the effective life of the heat exchanger, the lives of conduits and the heat exchanger itself have been found to be extremely short in view of the rapid disintegration occasioned by electrolysis and the corrosive effects of the raw sea water.

A broad object of this invention is the provision of a device and method for the protection of metal parts from the damaging effects of electrolysis and corrosion, ordinarily present when such metal parts are exposed to raw sea water in use.

A more limited object of this invention is the provision of a device which will effectively prevent the aforesaid damaging action in an effec-

5 tive and economical manner and provide a sense of security to interested persons because the parts of the device are simple, accessible and subject to inspection and replacement with ease at needed intervals.

Another object of this invention, through the use of the device and method disclosed, is the elimination of the necessity of using bulky, costly and relatively inefficient devices, such as the heat exchanger used in marine installations as described above, in many instances where such devices are now considered to be indispensable from a practical point of view. It can be seen readily that better effects could be obtained, in a marine engine for example, if it were possible to use cool raw sea water, from an unlimited supply, to cool the engine rather than to employ a heat exchanger which, obviously, cannot be perfectly efficient.

10 20 A further object of this invention is the provision of a device into which the raw sea water is introduced and brought into contact with spaced zinc plates which, when properly grounded, will change the character of the sea water so that it will not have the damaging electrolytic and corrosive characteristics described above.

25 A further object is the provision in such a device of plate mountings and electrical connections which will ensure, over a long period of time, the effectiveness of the device, even when the main body portions of the plates have been materially disintegrated by action of the raw sea water upon them.

30 35 This invention, therefore, comprises a method by which metal parts are protected from deleterious action of sea water by treating the sea water prior to the time it comes into contact with said metal parts, and a device for protecting said metal parts which comprises a container into which the raw sea water is introduced, spaced metallic plates which are affected by electrolysis, ground connections joining said plates and a ground, and means for mounting said plates to ensure effective action of the device.

40 45 A more complete understanding of my invention may be had in connection with the following description, by reference to the accompanying drawings in which:

50 Figure 1 is a longitudinal sectional view of the casing or container of the device with certain interior parts in elevation.

Figure 2 is a top plan view of the device shown in Figure 1, but with the cover plate removed.

Figure 3 is a top plan view of a modified form

of the device which is provided with a multiplicity of outlets.

Figure 4 is an exploded view of the interior parts of the device with the conducting bar removed from its normal position.

Figure 5 is a diagrammatic view of my device in an assembly for marine use.

Figure 6 is a detailed view of a modified arrangement of ground connection.

Referring now to Figure 1, my device comprises a casing 10, of box-like form, preferably made of red brass and provided with an interiorly threaded intake boss 11, and a similarly interiorly threaded outlet boss 12. The base of the casing is provided with an interiorly threaded boss 13 for the reception of a drain plug 14.

Referring now to Figure 2, the opposite side walls of the casing are provided with slots 15, which constitute holding guides for zinc plates 16 and 17, which are mounted adjacent the outlet end of the casing. Adjacent the inlet end is provided a chamber for the reception of a foraminous plate or screen 18, which carries a flat flanged base 19 and upwardly extending flanges 20, which are curved, as at 21, to permit easy removal of the plate 18 by a simple tilting away from oppositely disposed vertically extending ribs 22, as shown in Figure 1, when the cover plate 23 is removed, as shown in Figure 2.

It will be noted that zinc plates 16 are provided with apertures 24, while plates 17 are provided with apertures 25, which are out of alignment with apertures 24, when the plates are in proper and assembled relationship. Because of this arrangement, water flowing through the inlet to the outlet will pursue a circuitous route and come effectively into contact with large exposed surfaces of the zinc plates. The top edges of plates 16 are notched, as at 26, while plates 17 are notched, as at 27, for the reception of an elongated zinc plate 28, which rests snugly within the said notches of the plates 16 and 17, thus forming a good electrical connection between all of the plates.

The casing 10 carries a horizontally extending flange 31 around its upper end, and this flange carries threaded openings 29 which receive a plurality of cap screws 30, which pass through openings in the outer edge of cover plate 23 and hold the said cover securely in position.

Cover plate 23 carries a hollow dome-like boss 32 which receives an expansion spring 33, which presses upon the upper surface of plate 28, and rests upon the interior upper wall of boss 32, to which screw 34 securely anchors the spring 33. Spaced from the boss 32 is a boss 35, which is drilled and tapped, as at 36, to receive a threaded connection for a ground wire.

Referring now to Figure 3 in which a modified form of the device is shown, a casing, similar to casing 10, is provided except that additional outlets 37 and 38 are provided for attachment to two conduits in addition to the one which may be attached to outlet 39. The cover plate of this casing of Figure 3, is similar to that of the casing shown in Figure 1, and all interior parts are similar to those shown in the device of Figure 1.

With respect to the devices of both Figures 1 and 3, the outlets and inlets are shown to be interiorly threaded bosses, but it is well known that outwardly extending coupling flanges, generally similar to flange 31 at the upper end of casing 10, with threaded sockets for the coupling of flanged conduits, may be provided wherever desired.

Referring now to Figure 5, the device 10 of Figure 1 is illustrated in a diagrammatic showing of a boat, such as one in which the device is suitable for use. In the bottom of the hull, a sea cock 40 is provided, and a conduit 41, controlled by valve 42, conveys sea water to a conduit 43, which conveys water to the interior of device 10 (through foraminous plate 18 and through the openings of plates 16 and 17, as described above).

From casing 10 water proceeds, after treatment by device 10, through conduit 44, valve 45 and conduit 46 to heat exchanger 47, and passes around the tubes of heat exchanger 47, which carry the fresh water which passes through conduits 48 and 49 connecting the heat exchanger 47 and the engine shown in diagrammatic form. From the heat exchanger 47, water passes through conduit 50 to a suction pump 51, through conduit 52 and to an outlet 53, for return to the sea.

A ground wire 54 is connected to the boss 35 of device 10 and to the block of the engine in cases where the propeller shaft of the boat is connected directly to the crank shaft of the engine, thus giving a good electrical connection to the sea water on the outside of the hull of the boat.

In cases in which a clutch between the engine and the propeller shaft is employed, a ground connection of the type indicated in Figure 6 may be employed. In this modified connection, a ground wire 55 is connected to the device 10 in the manner described above and to a terminal 56 carried by a leaf spring 57 which is mounted upon an insulated support 58, and conductor 59 connects terminal 56 with terminal 60, which carries a current conducting brush 61, which rides upon propeller shaft 62, and thus, an appropriate ground connection between the device 10 and the sea.

Due to the fact that electrolysis occurs within my device, the zinc plates 16 and 17 eventually become covered with a fine coating (powdery when dry) and it will be necessary occasionally to remove this coating to keep the device operating efficiently. Therefore, the cover plate 23 may be removed, the plates 16 and 17 may be raised from their guides, and the coating may be brushed or scraped off. Periodic inspection is easy and replacement of the zinc plates, when needed, is a simple operation.

In instances where it is possible, by virtue of the effectiveness of the device 10 described above, to dispense with a heat exchanger, such as that shown at 47 in Figure 5, the conduit 46 could be connected directly with the intake conduit of the engine, while the conduit 50 could be connected with the outlet conduit of the engine so as to provide cool sea water directly to the engine without the attendant loss of efficiency in cooling. Thus, the bulky and expensive heat exchanger could be dispensed with and yet the interior of the cooling jacket of the engine would be protected from a deleterious action of electrolysis.

There are many other installations in which my method and device may be employed, and I do not wish to be limited in the uses to which my method and device may be put, nor do I wish to be limited beyond a proper scope and spirit of the appended claims in respect of modifications or adaptations which may occur to those skilled in the art.

What is claimed is:

75 1. In combination, a boat having an engine

therein, a fresh water circulatory system in said engine, a heat exchanger operatively associated with said fresh water system and adapted to have sea water pass therethrough, and a sea water treating device for reducing the corrosive effect of sea water prior to introduction to said heat exchanger, said treating device comprising a casing made of a metal having good electrical conducting properties, and formed with an inlet for fresh sea water and an outlet for treated water communicating with said heat exchanger, a plurality of zinc plates arranged in spaced relation in said casing, and over which sea water is adapted to pass, means for conductively connecting said plates, and means for grounding said plates to said engine.

2. In combination, a boat having an engine therein, a fresh water circulatory system in said engine, a heat exchanger operatively associated with said fresh water system and adapted to have sea water pass therethrough, and a sea water treating device for reducing the corrosive effect of sea water prior to introduction to said heat exchanger, said treating device comprising a casing made of a metal having good electrical conducting properties, and formed with an inlet for fresh sea water and an outlet for treated water communicating with said heat exchanger, a plurality of zinc plates arranged in spaced relation in said casing, each of said plates being formed with a plurality of holes with the holes in any one plate being in staggered relation with respect to the holes in the next adjacent plates, means for conductively connecting said plates, and means for grounding said plates to said engine.

3. In combination, a boat having an engine therein, a fresh water circulatory system in said engine, a heat exchanger operatively associated with said fresh water system and adapted to have sea water pass therethrough, and a sea water treating device for reducing the corrosive effect of sea water prior to introduction to said heat exchanger, said treating device comprising a casing made of brass and formed with an inlet for fresh sea water and an outlet for treated water communicating with said heat exchanger,

a plurality of zinc plates removably arranged in spaced relation in said casing and over which sea water is adapted to pass, means for conductively connecting said plates, and means for grounding said plates to said engine.

4. In combination, a boat having an engine therein, a fresh water circulatory system in said engine, a heat exchanger operatively associated with said fresh water system and adapted to have sea water pass therethrough, and a sea water treating device for reducing the corrosive effect of sea water prior to introduction to said heat exchanger, said treating device comprising a casing made of brass and formed with an inlet for fresh sea water and an outlet for treated water communicating with said heat exchanger, said casing having opposed side walls, the inner faces of which are formed with spaced grooves, with the grooves in one side substantially opposite to the grooves in the other side, a plurality of zinc plates each of which has its side edges received in a set of said grooves whereby said plate is removably positioned in said casing, each of said plates being formed with a plurality of openings with the openings in any one plate being in staggered relation with respect to the openings in the next adjacent plates, a contact bar engaging the top edges of said zinc plates, spring means urging said bar against said plates, and an electrical connection between said bar and said engine.
